UNITED STATES PATENT OFFICE.

HARRY C. WATSON, OF CANTON, OHIO.

APPARATUS FOR SHAKING OUT CASTINGS.

Application filed May 22, 1920. Serial No. 383,392.

To all whom it may concern:

Be it known that I, HARRY C. WATSON, a citizen of the United States, residing at Canton, in the county of Stark and State of Ohio, have invented a new and useful Improvement in Apparatus for Shaking Out Castings, of which the following is a full, clear, and exact description, reference being had to the accompanying drawings, forming a part of this specification, in which—

Figure 1 is a plan view, partly broken away, of a shaking out machine embodying my invention.

Figure 2 is a section on the line II—II of Figure 1.

Figure 3 is a sectional plan view, partly broken away, of a portion of the actuating mechanism, and

Figure 4 is a section on the line IV—IV of Figure 3.

My invention has relation to apparatus for shaking out castings from the sand in which they are cast; and is designed to provide an efficient and convenient apparatus by means of which the work may be efficiently performed in a manner which will not injure either the castings or the flask in which the sand molds are made.

My invention also provides a machine or apparatus of this character, by means of which a plurality of castings may be shaken out at the same time. In its preferred form, it also provides a machine or apparatus of this character in which either a portion of the shaking out table, or the entire table may be utilized at any particular time for shaking out operations, thus permitting the capacity of the apparatus to be varied in accordance with requirements, and also permitting one portion of the table to be used in shaking out while the other side is being unloaded and reloaded.

My invention also provides means whereby the sand and dirt shaken from the castings is readily taken care of and removed.

The nature of my invention will be best understood by reference to the accompanying drawings in which I have shown a preferred embodiment of my invention and which will now be described; it being premised, however, that various changes can be made in the details of construction, arrangement and combination of the various parts without departing from the spirit and scope of my invention as defined in the appended claims.

In these drawings, I have illustrated a shaking out table comprising a series of spaced, parallel, longitudinally extending bars 2 which are fixedly secured to any suitable bed or foundation, such as indicated at 3. 60 4 designate vertically movable bars which are placed in alternating relation to the bars 2 and which are adapted to be actuated to raise the castings to be shaken out and drop them back upon the table in a manner to give an effective shaking out action. These bars are pivoted at 5 beyond the rear end of the table and are actuated by mechanism 65 such as now to be described.

6 designates an electric motor whose armature shaft 7 is coupled to a drive shaft 8 (see Figure 3) through a suitable coupling 9 which is preferably of a non-rigid or semi-resilient character. The shaft 8 carries a 70 worm 10 which meshes with a worm wheel 11 on a transverse shaft 12 also having two spaced apart spur toothed pinions 13. These pinions mesh, respectively, with two gear wheels 14 which are sleeved upon opposite 75 end portions of a crank shaft 15. The inner faces of the gears 14 are cut away circularly concentrically with the axis of the crank shaft, as indicated at 16, these cutaway portions being adapted to partially receive 80 therein the segmental cheek members 17 between which is formed the crank pin 18. The outer ends of the cheek members 17 are curved to conform approximately to the inner periphery of the cutaway portion 16. 85 Each of these cutaway portions is provided with a projection 18^a which is designed to engage the adjacent cheek piece and thereby form a driving connection for the crank shaft throughout a portion of the revolution 90 of the gear wheel 14.

The crank pin 18 is connected by a pitman 19 with an arm 20 on the transverse rocker shaft 21. This shaft also carries, at 100 opposite sides of the arm 20, two rocker arms 22 which are loosely sleeved on the shaft 21 and are designed to be connected thereto through the medium of the respective clutches 23. The movable member of each of these clutches is arranged to be 105 moved into and out of clutching engagement with the clutch portion of the arm 22 by any suitable means such as the hand operated screw shaft 24. One of these clutches 110 with a portion of its actuating screw shaft is shown in detail in Figure 3.

25 designate pairs of links which connect

the rocker arms 22 with three armed bell crank levers 26 of a second rocker shaft 27, which is cut in two, intermediate the two sets of connections 25. The links 25 are arranged in pairs both above and below the shafts 21 and 27 in the manner shown in Figures 1 and 2. The third arm of each bell crank 26 is connected by a link 28 to the adjacent end of one of the shaker bars 4 before described.

29 designates flooring placed below the shaking out table and which is inclined downwardly and centrally in the manner of a hopper to a discharge opening 30 which is arranged to discharge the sand and dirt shaken from the castings onto any suitable conveyer, such as the endless conveyer indicated at 31.

The operation is as follows:

20 The sand molds containing the castings to be shaken out are placed upon the table and the machine started. During a portion of each revolution of the gears 14 the projections 18^a thereof will engage one of the 25 cheek members of the crank shaft 15 in the manner shown in Figure 4 to form a driving engagement therewith. The connections between the shaft 15 and the vertically movable shaker bars 4 are so arranged that during 30 this portion of the movement of the gearing, which is substantially 180 degrees of rotation thereof, said shaker bars will be raised to their uppermost positions. The crank pin 18 will then have passed its upper center, 35 and the weight of the castings and sand on the bars 4 will cause said bars to drop, the crank pin 18 during this dropping movement running ahead of the gear wheels 14 so that the crank shaft will remain stationary until 40 the projections 18^a again catch up and come into contact with the cheek members 17. This sudden dropping of the shaker bars 4 to the level of the fixed bars 2 entirely under the accelerative effect of gravity, causes a 45 very effective jarring movement to be exerted upon the sand and castings. This mechanism produces a true gravity drop such as occurs in freely falling bodies, modified only by the friction in the mountings of 50 the mechanism which come into play at this time. The sand and dirt thus shaken from the castings fall through the table onto the flooring 29 and thence to the conveyer 31, by which it is removed to any desired point.

55 By means of the clutches 23 before described, it will be readily seen that either one or both sections of the table may be used simultaneously for shaking out operations, depending upon the capacity required.

60 This also permits one section of the table to be used in shaking out, while previously shaken out castings are being unloaded from the other sections and a new load of castings is being placed thereon.

65 The machine or apparatus is simple and

positive in its construction and mode of operation, and exerts a shaking operation of a character which will not injure either the castings or flasks which may be contained in the said molds. Its use enables a large number of castings, particularly relatively small castings, to be shaken out at the same time, thus enabling the shaking out operations to be rapidly performed.

I claim:

1. Apparatus for shaking out castings, comprising a table having a series of spaced fixed bars, and a series of alternating vertically movable bars, together with actuating connections for the movable bars, said connections being operative to produce a positive raising of the movable bars and then inoperative to permit a substantially true gravity drop thereof independently of further movement of said connections, substantially as described.

2. Apparatus for shaking out castings, comprising a table having a series of spaced fixed bars, and a series of alternating vertically movable bars, together with actuating connections for the movable bars, said actuating connections having means for raising said bars and then permitting them to drop independently of further movement of said connections under the weight of the load thereon, substantially as described.

3. A shaking out table for castings, comprising a series of fixed bars, a series of vertically movable bars, an endless take-off conveyer below the table, and means for directing the sand and dirt shaken from the castings to said conveyer, substantially as described.

4. A shaking out table having a series of vertically movable shaking bars, a rocker shaft having actuating connections with said bars, and means for positively actuating said rocker shaft in one direction and permitting said shaft to turn in the reverse direction entirely under the action of the load on said bars independently of further movement of said means after the rocker shaft has completed its movement in one direction, substantially as described.

5. A shaking out table having a plurality of vertically movable shaking bars, a rocker shaft having actuated connections with said bars, a crank shaft, actuating connections between the crank shaft and rocker shaft, and gearing for actuating the crank shaft, said gearing having a connection with the crank shaft which will permit the latter to move ahead of the gearing during a portion of each revolution of the gearing.

6. Apparatus for shaking out castings, comprising vertically movable shaker bars, a crank shaft having actuating connections with said bars, a pair of gears loosely sleeved on said crank shaft at opposite sides of its crank pin, means for positively actuating

said gears, and driving connections between the gears and the crank shaft which will permit the crank shaft to move independently of the gears during a portion of each revolution of the gears, substantially as described.

7. Shaking out apparatus, comprising a shaking out table having a plurality of vertically movable shaking bars, and a single means having operative connections for simultaneously actuating all or only a portion of said bars, substantially as described.

8. A shaking out table having a plurality of vertically movable shaking bars, a rocker shaft, said shaft being formed in two sections, actuating connections between said shaft and the shaking bars, and a single means whereby either or both of said sections may be actuated, substantially as described.

9. A shaking out table having a plurality of vertically movable shaking bars, a rocker shaft having actuating connections with said bars, a crank shaft, actuating connections be-

tween the crank shaft and rocker shaft, and gearing for actuating the crank shaft, said gearing having a connection with the crank shaft which is effective only during one-half of the revolution of the crank shaft thereby permitting the crank shaft to move ahead of the gearing during the remainder of each revolution thereof, substantially as described.

10. Apparatus for shaking out castings, comprising a table having a series of spaced fixed bars, and a series of alternating vertically movable bars, together with actuating connections for the movable bars, and rotary means effective during one-half of each rotation thereof for positively operating said actuating connections for raising said bars, and then permitting said bars to drop independently of said connections under the weight of the load thereon, substantially as described.

In testimony whereof, I have hereunto set my hand.

HARRY C. WATSON.
